UNITED STATES PATENT OFFICE.

JAMES ALBERT WESTMORELAND, OF VIVIAN, LOUISIANA.

SAND TRAP FOR OIL WELLS.

Application filed April 17, 1922. Serial No. 553,758.

To all whom it may concern:

Be it known that I, JAMES A. WESTMORELAND, a citizen of the United States, residing at Vivian, in the parish of Caddo and State of Louisiana, have invented certain new and useful Improvements in Sand Traps for Oil Wells; and I do declare the following to be a full, clear, and exact description of the invention, such as will enable others skilled in the art to which it appertains to make and use the same.

This invention relates to an improved sand trap for use in conventional types of oil wells and the like.

15 The principal object of the invention is to generally improve sand traps for this purpose by providing one which simply comprises a plug adapted to be connected with a pipe coupling and to be arranged between the ends of the pipe to provide a partition, this plug being constructed so that a valved conduit can be connected therewith for controlling the passage of the fluid therethrough.

25 Other objects and advantages of the invention will be apparent during the course of the following description.

In the accompanying drawings forming a part of this specification and in which like 30 numerals are employed to designate like parts throughout the same:

Figure 1 is an elevational view with parts broken away and shown in section, of a conventional type of oil well equipped with a 35 sand trap constructed in accordance with this invention.

Figure 2 is an enlarged sectional view of the intermediate portion of the device disclosing the structure of the sand trap more 40 clearly.

In the drawings, the usual well casing is shown as being composed of a suitable number of sections of pipe 1 connected together by the usual forms of couplings 2. The 45 traveling valve is designated generally by the numeral 3 and the usual combined anchor and strainer by the numeral 4. It is between the last named part and the traveling valve that the sand trap is preferably 50 located and actual use of the trap has disclosed that it will work very effectively if arranged at the juncture of the well casing and strainer. Therefore, I have so shown it.

To enable a clear understanding of the 55 trap to be obtained, I will direct especial attention to the enlarged sectional view ap-

pearing in Fig. 2. In forming the trap, I simply make use of an externally screw-threaded plug 5 and I arrange this between the ends of the pipe 1 and engage the screw- 60 threads thereof with the internal screw-threads of the usual coupling 2. By disposing the plug at this point, a partition is formed on which the sand settles. The plug is formed with a central bore 6 and is 65 equipped with an upstanding tubular extension 7 which forms an integral part thereof. This extension is internally screw-threaded at its upper end and a conduit 8, having a check valve 9 at its upper end, is connected 70 thereto. The aforesaid bore 6 is internally screw-threaded at its lower end and a relatively small depending tube 10 is connected thereto to restrict the passage of fluid and sand from below the partition into the chamber formed by the arrangement described. 75 In practice, the end of the strainer 4 and pipe 1 will be disposed in abutting relation with the plug to prevent accidental displacement thereof. In operation, the oil and sand 80 carried thereby is drawn through the apertures in the anchoring pipe 4 and is sucked upwardly through the pipe 10 and valved conduit and the sand is permitted to settle down and deposit on the upper side of the 85 plug and is trapped at this point and prevented from being carried upwardly and interfering with the operation of the traveling valve. Consequently, the latter is rendered very effective and the usual packing cups 90 associated therewith are prevented from being unduly worn.

It is obvious from the foregoing description that the plug can be easily and very inexpensively manufactured and used at the 95 point indicated with any suitable type of a valved conduit. In view of its extreme simplicity and low cost, the invention is doubtless an improvement over other prior patented and marketed inventions for the same 100 purpose.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the 110

invention. However, I wish it to be understood that minor changes coming within the scope of the invention as claimed may be resorted to if desired.

5 I claim:

In a sand trap for wells, a combined anchor and strainer pipe, tubing of the same diameter as said pipe, a coupling connecting said tubing with said strainer pipe, said 10 coupling being of uniform diameter and having internal screw-threads extending from end to end, a plug having a threaded periphery engaged with the threads of said

coupling, said plug being arranged between the ends of said tubing and pipe to form a 15 partition and to provide a sand trap, said plug being formed with a central opening and with a neck rising from said opening to permit the passage of the oil from the strainer into the tubing, said neck being 20 comparatively small, and a comparatively small valved conduit connected to and rising from said neck.

In testimony whereof I have hereunto set my hand.

JAMES ALBERT WESTMORELAND.
